UNITED STATES PATENT OFFICE

PHILIP K. DEVERS, OF LYNN, AND IRVIN F. HOOPER, OF SAUGUS, MASSACHUSETTS, ASSIGNORS TO GENERAL ELECTRIC COMPANY, A CORPORATION OF NEW YORK

SPARK PLUG

Application filed December 17, 1928. Serial No. 326,433.

The present invention relates to the construction of spark plugs for internal combustion engines. It is the object of our invention to provide a construction whereby 5 a reliable and long-lived spark plug containing an insulator composed of refractory vitreous material may be provided.

Various attempts have been made to utilize vitreous materials, as for example, fused 10 silica and refractory glass, for the insulating member in spark plugs, but with the constructions heretofore employed weaknesses have so frequently developed in the 15 vitreous member that such plugs have not been sufficiently reliable to warrant their adoption on a large scale in commercial manufacture. In such prior plugs the vitreous insulator has been constructed either with an angular shoulder to which the pressure 20 required for sealing the plug has been applied or the vitreous insulator has been made tapered in shape and held under pressure in a tapered casing. Either construction results in strains before or during service which 25 after comparatively short service cause failure of the plugs.

In accordance with our invention we have provided an improved spark plug containing a vitreous insulator having a generally 30 elongated shape and an enlargement having convex bearing surfaces of substantially spherical configuration. Pressure is applied to the spherical bearing surfaces whereby the 35 enlargement is put under compression in order to produce a gas-tight seal, but shearing or bending stresses are avoided. The novel features of my invention will be pointed out with greater particularity in the appended claims.

40 The accompanying drawing shows several embodiments of our invention. Figs. 1 and 2 show longitudinal sections of spark plugs containing vitreous insulators embodying our invention; Figs. 3 and 4 are longitudinal 45 sections of modified forms of hollow insulators with a conductor mounted therein; and Figs. 5 and 6 illustrate modifications also in vertical section.

Referring to Figs. 1 and 2, the spark plug 50 includes a casing 1 which is screw-threaded

externally at its lower end for engagement with a screw-threaded orifice in the internal combustion engine. This casing preferably consists of steel, brass, nickel or other suitable material. This casing is screw-threaded 55 internally at its upper end for engagement with a retaining nut 2 whereby pressure is applied upon the vitreous insulator 3 through the soft metal gaskets 4 and 5. These gaskets 4 and 5 preferably consist of soft copper. 60 The lower gasket 5 may be omitted in some cases.

The insulator 3, which preferably consists of fused silica, has a bulbous enlargement 6 intermediate a shaft 7 and a shaft 8 surrounding the firing tip of the conductor 9. The areas of this enlargement upon which pressure is applied should approximate a true spherical surface, very closely in their 65 curvature. The bearing surfaces of the 70 spheroidal enlargement with which the gaskets 4 and 5, or other sealing means, engage are spaced apart leaving the intervening portion free. These bearing surfaces are positioned in what may be termed a median 75 zone of the enlargement, spaced away from the shafts 7 and 8. The silica is placed under compression in this zone without shear or tension. This spherical shape has two important functions; first, it distributes in a 80 most favorable way the stresses caused by mechanical pressure and thermal expansion. The elasticity of silica being nearly perfect, such a spherical body under pressure will adapt itself to the expansion and contraction 85 of the external casing during temperature changes to maintain a gas-tight joint at all times. Secondly, the spherical surfaces reflect radiant energy from the firing tip in the direction of the external casing and thus 90 dissipate the heat. In the absence of a structure whereby the heat derived from the firing tip is reflected to the casing where it is dissipated, the transmission of heat through a silica member longitudinally would be sufficient to cause damage to external parts and the central conductor. The spheroidal enlargement merges with the shafts 7 and 8 by a non-angular contour, as shown in the 95 drawing, the merging surfaces preferably be-

ing reversely curved, or of concave curvature.

A longitudinal passage extends through the silica insulator 3 through which passes the conductor 9 having a slightly smaller diameter than the bore of the passage. As shown in the drawing the diameter of the conductor 9 is materially less than the diameter of the insulator 3. The space between the conductor and the walls of the passage is filled with a cement 17, for example, a mixture of kaolin, china clay, and water glass, forming a sealing means which is inherently yieldable and will not cause the insulator to crack when the conductor 9 expands due to heating. Such a cement is commonly used in spark plug manufacture. A conductor 10 is affixed to the casing 1 and extends toward the conductor 9, being separated by a required sparking gap.

In Fig. 1 a spacing ring 11, which may consist of copper, has been provided between the retaining nut 2 and the silica insulator 3 in order to damp out vibrations of the insulator during service. This ring may be introduced by pouring molten metal into the space between the nut 2 and the insulator 3, a suitable plug 12 of highly refractory metal, such as powdered silica, magnesium, zirconia, or the like being provided to prevent the molten metal from coming into contact with the spherical surface of the insulator. In the construction shown in Fig. 2 the members 11 and 12 have been omitted, as they are not essential in all cases.

As shown in Fig. 3, the enlargement 6 of the insulator 3 is hollow. The enlargement, therefore, has two reflecting surfaces from which radiant energy is reflected and dissipated. The space between the conductor 9 and the spherical enlargement 6 may be filled wholly or partly with a spark plug cement 17'. When it is desired to provide a hollow, spherical enlargement, it is convenient to employ tubing for the fabrication of the insulator 3, the tubing being shaped by gas pressure, applied internally while the tubing is heated to plasticity preferably within a mold of suitable form.

In the modification of our invention illustrated by Fig. 4, the shaft 7 of the silica insulator has a somewhat larger bore than in the insulators of Figs. 1 to 3 and a tube 13 of silica surrounds the conductor 9 up to the junction of the spherical enlargement 6 and the firing tip 8. Preferably the end of the silica tube 13 is united by fusion with the shaft 7 of the insulator, as indicated at 14.

The shaft 7' of the silica insulator shown in Fig. 5 is tapered to reduce its mass at its external end in order to minimize the effect of mechanical vibration. In both of the modifications of the silica insulator shown in Figs. 5 and 6 a longer shaft surrounds the firing tip than in the devices illustrated by

Figs. 1 to 4. Such insulators are adapted for use in certain special types of engines, for example, airplane engines.

The spark plug shown in Fig. 6 has a gasket 15 of modified shape. This gasket which may consist of copper or other soft metal is forced by the screw threaded nut 2 against both the vitreous insulator 16 and the shell 1, the gasket 15 being shaped to make a line contact. Such a plug may be made gas-tight by hand.

What we claim as new and desire to secure by Letters Patent of the United States, is:

1. A spark plug comprising an elongated insulator of vitreous silica, said insulator having a hollow bulbous enlargement and a hollow shaft integral therewith, a conductor extending longitudinally through said insulator, a tube of vitreous silica extending through said shaft and said enlargement closely surrounding said conductor, a casing for said insulator, and means for making a gas-tight seal between said insulator and said casing.

2. A spark plug for internal combustion engines comprising a metal shell, elongated insulating means therein consisting essentially of vitreous silica having at one end a shaft, at the opposite end a firing tip, and intermediate thereto an enlargement having a convex spherical surface merging with said shaft and tip by concave, non-angular transition surfaces and having a longitudinal passage, a conductor of small diameter as compared with the thickness of the insulating means extending through said passage leaving a space surrounding said conductor, a cement sealing the space surrounding said conductor in said passage, and means for exerting sealing pressure between said shell and the spherical surface of said enlargement.

In witness whereof, we have hereunto set our hands this 14th day of December, 1928.

PHILIP K. DEVERS. 11
IRVIN F. HOOPER.
